(57) **CLAIM**

We claim the ornamental designs for dispensing closure for a container, as shown and described, except as disclaimed herein.

DESCRIPTION

FIGS. 1-7 illustrate various views of a dispensing closure, shown in a closed condition, wherein:

FIG. 1 is a top view of the dispensing closure;

FIG. 2 is a bottom view of the dispensing closure;

FIG. 3 is a left side view of the dispensing closure;

FIG. 4 is a right view of the dispensing closure;

FIG. 5 is a front side view of the dispensing closure;

FIG. 6 is a rear view of the dispensing closure; and

FIG. 7 is an upper perspective view of the dispensing closure.

FIGS. 8-14 illustrate various views of the dispensing closure of FIGS. 1-7, shown in an open condition, wherein:
FIG. 8 is a top view of the dispensing closure;
FIG. 9 is a bottom view of the dispensing closure;
FIG. 10 is a left side view of the dispensing closure;
FIG. 11 is a right view of the dispensing closure;
FIG. 12 is a front side view of the dispensing closure;
FIG. 13 is a rear view of the dispensing closure; and,
FIG. 14 is an upper perspective view of the dispensing closure.
